UNITED STATES PATENT OFFICE.

FREDERICK W. CASSIDY, OF PHILADELPHIA, PENNSYLVANIA.

NON-REFILLABLE BOTTLE.

1,156,346.

Specification of Letters Patent.

Patented Oct. 12, 1915.

Application filed April 8, 1915. Serial No. 19,882.

To all whom it may concern:

Be it known that I, FREDERICK W. CASSIDY, a citizen of the United States, residing at Philadelphia, in the county of Philadelphia and State of Pennsylvania, have invented certain new and useful Improvements in Non-Refillable Bottles, of which the following is a specification.

My invention relates to improvements in 10 non-refillable bottles, the object of the invention being to provide an attachment for the neck of the bottle which can be permanently secured in the neck of the bottle, and which will permit the contents of the bottle to be 15 readily poured out, but preclude any fraudulent attempt to refill the bottle.

A further object is to provide a non-refillable bottle which embodies in its construction an improved arrangement of baffles 20 to prevent fraudulent manipulation of the valve.

A further object is to provide improved 25 means for securing the attachment within the neck of the bottle, and securely holding the attachment against movement.

With these and other objects in view, the invention consists in certain novel features of construction and combinations and arrangements of parts as will be more fully 30 hereinafter described and pointed out in the claims.

In the accompanying drawings: Figure 1 is a view in longitudinal section illustrating my improvements. Fig. 2 is a view in transverse section on the line 2—2 of Fig. 1. Fig. 3 is a perspective view of the valve moving weight. Fig. 4 is a view in elevation of the spring band 6. Fig. 5 is a view in transverse section on the line 5—5 of Fig. 1, and Fig. 6 is a view similar to Fig. 1 illustrating a modified form of baffle.

1 represents a bottle having a neck 2, provided at its juncture with the bottle with an internal annular shoulder 3, and also provided between the end of the neck and the shoulder 3 with an internal annular groove 4.

5 represents the casing of my improved attachment. This casing and the parts integral therewith are formed with two half sections as shown clearly in Figs. 1 and 2. In other words, the casing is made in two separable parts, snugly fitting together and fitting within the bottle neck 2.

The lower end of the casing 5 bears 55 against shoulder 3, and a spring band 6 is located in a groove 7 around the casing 5,

and is provided at its upper edge with outwardly projecting tongues 8, which engage in the annular groove 4, and securely hold the casing against movement. This band is 60 shown in elevation in Fig. 4, in which it will be noted that it is provided at its upper edge with the outwardly projecting tongues 8 above referred to, and at its lower edge with inwardly projecting tongues 9. 65

These inwardly projecting tongues engage the lower wall of groove 7, and prevent any longitudinal movement of the casing in the bottle neck. The tongues 9, between their ends, are bowed outward as shown at 10, 70 and bear against the inner face of bottle neck 2, operating to prevent any possibility of lateral movement of the casing and effectually holding the casing in the neck.

The band 6 is provided between its upper 75 and lower edges with an internal bead 11, which projects in a correspondingly shaped groove 12 in the casing 5, and effectually holds the two sections of the casing together, while the latter is assembled and positioned 80 in the bottle neck.

Casing 5 is provided at its lower end with a restricted opening 13, forming a conical valve seat 14, against which a float valve 15 normally engages to close the bottle. The 85 float valve 15 is preferably in the form of a ball and made of any suitable material which will withstand the action of the contents of the bottle, and which will float.

Above the valve 15, I locate a movable 90 weight 16. This weight is shown in perspective in Fig. 3, and is of general spider form. That is to say, the weight comprises a central relatively thin disk 17 formed integrally with a circular series of radially positioned 95 ribs 18, the ribs flush with the lower edge of the disk 17, but extended an appreciable distance above the upper face of the disk, so that while the principal function of the weight is to compel the valve to close, it also 100 operates as a baffle to prevent tampering of the valve by a wire or other instrument inserted in the bottle neck.

The downward movement of the weight is limited by an annular shoulder 18^a in casing 105 5, so that the weight operates to move the valve to closed position, but does not exert any material pressure on the same which might tend to jam the valve and prevent its opening at the desired time.

The upward or outward movement of the weight is limited by an internal annular

flange 19, which forms a restricted opening 20, and also operates as a baffle.

Above the internal flange 19, the body portion 5 is provided with two baffles 21 and 22, located at right angles to each other. These baffles 21 and 22 constitute enlargements which are narrowest at their center and widen or enlarge from the center to their outer ends. These baffles 21 and 22 as well as the flange 19, are integral with the casing 5, while the weight 16 and valve 15 are separate parts which are located in the casing, before the two halves of the casing are brought together and secured by the spring band 6.

In the modification shown in Fig. 6, the parts are constructed precisely as the preferred form, except that below the lower baffle 21, I provide a spiral baffle 23 which is integral with the lower baffle 21, and also with an internal annular flange 24 in the casing.

I have given the parts in this modification the same reference numerals as applied to 25 the same parts of the preferred form.

The operation is as follows: When the bottle is tilted to pour out the contents, the weight 16 will move away from the valve 15, and allow the latter to move from its seat 14. 30 The liquid in the bottle will then flow around the valve between the ribs 18 of the weight 16, through the opening 20, and around the baffles 21 and 22, so that the outward flow of the liquid is free. When the bottle is 35 turned to its normal position, the weight 16 will quickly move the valve 15 to close the bottle. Any attempt to refill the bottle is baffled, because the weight 16 will close the valve whenever the bottle is in upright position, and any attempt to force liquid into 40 the bottle either by pressure or by submerging the bottle, will be prevented by the movement of the float valve 15 to its seat.

The arrangement of baffles prevents any 45 possibility of the tampering of the valve by a wire or instrument inserted through the neck of the bottle, and the casing is securely locked in the bottle neck, so that it cannot be removed.

50 While I have illustrated what I believe to be a preferred embodiment of my invention, I would have it understood that I do not limit myself to the precise details set

forth, but consider myself at liberty to make such changes and alterations as fairly fall 55 within the spirit and scope of the appended claims.

Having thus described my invention, what I claim as new and desire to secure by Letters Patent is:

1. The combination with a bottle neck, of a casing in the bottle neck, a valve in the casing, a baffle in the casing above the valve, said casing comprising two longitudinal sections, a spring band around the casing securing the halves together, said casing and neck having annular grooves receiving the spring band, the upper edges of the band engaging in the groove of the bottle neck, the lower edges of the band engaging in the 70 groove of the casing, and said band at a point above its lower edge having outwardly bowed portions bearing against the face of the bottle neck, and said band having an inwardly projecting bead between its ends 75 bearing against the casing, substantially as described.

2. The combination with a bottle neck, of a casing secured within the bottle neck, said casing having a valve seat at its lower end, 80 and a plurality of internal baffles at its upper end, a weight in the casing located above the valve, said casing constructed to limit the movement of the weight in both directions, said casing comprising two longitudinal sections, a spring band around the casing securing the halves together, said casing and neck having annular grooves receiving the spring band, the upper edges of the band engaging in the groove of the bottle neck, 85 the lower edges of the band engaging in the groove of the casing, and said band at a point above its lower edge having outwardly bowed portions bearing against the face of the bottle neck, and said band having an inwardly projecting bead between its ends 90 bearing against the casing, substantially as described.

In testimony whereof I have signed my name to this specification in the presence of 100 two subscribing witnesses.

FREDERICK W. CASSIDY.
